US0D1082584S

(12) **United States Design Patent** (10) Patent No.: **US D1,082,584 S**
(45) Date of Patent: ** Jul. 8, 2025

(54) **SONAR BUOY DEVICE**

(71) Applicant: **Garmin International, Inc.**, Olathe, KS (US)

(72) Inventors: **Brent E. Barberis**, Olathe, KS (US); **James E. Corbett**, Cary, NC (US); **Hsuan Tsun Wang**, San Francisco, CA (US)

(73) Assignee: **Garmin International, Inc.**, Olathe, KS (US)

(**) Term: **15 Years**

(21) Appl. No.: **29/912,678**

(22) Filed: **Sep. 21, 2023**

(51) LOC (15) Cl. **10-05**

(52) U.S. Cl.

USPC **D10/107**

(57) **CLAIM**

The ornamental design for a sonar buoy device as shown and described.

DESCRIPTION

FIG. 1 is a front perspective view of a sonar buoy device according to the present invention;

FIG. 2 is a bottom perspective view of the sonar buoy device;

FIG. 3 is a top view of the sonar buoy device;

FIG. 4 is a bottom view of the sonar buoy device;

FIG. 5 is a left side view of the sonar buoy device;

FIG. 6 is a right side view of the sonar buoy device;

FIG. 7 is a rear view of the sonar buoy device; and,

FIG. 8 is a front view of the sonar buoy device.

The broken lines shown in the drawings represent portions of the sonar buoy device that form no part of the claimed design.

1 Claim, 6 Drawing Sheets
